UNITED STATES PATENT OFFICE.

GIUSEPPE MAIELLA, OF BOSTON, MASSACHUSETTS.

DESIGN FOR A LAMP.

44,316.

Specification for Design.

Patented July 8, 1913.

Application filed March 31, 1913. Serial No. 758,038. Term of patent 7 years.

To all whom it may concern:

Be it known that I, GIUSEPPE MAIELLA, a subject of the King of Italy, residing at Boston, in the county of Suffolk and State of Massachusetts, have invented a new, original, and ornamental Design for Lamps, of which the following is a specification, reference being had to the accompanying drawing, forming part thereof.

Figure 1 is a side elevation; and Fig. 2 is an end view of a lamp showing my new design, the lamp being formed in fanciful similitude to a battleship, and being oval or oblong in shape, the figures showing in full all the distinctive ornamental features.

I claim:

The ornamental design for a lamp, as shown.

GIUSEPPE MAIELLA.
